UNITED STATES PATENT OFFICE.

JACKSON L. PRIOR, OF FAYETTEVILLE, NORTH CAROLINA.

NON-REFILLABLE BOTTLE.

SPECIFICATION forming part of Letters Patent No. 737,137, dated August 25, 1903.

Application filed May 25, 1903. Serial No. 158,585. (No model.)

To all whom it may concern:

Be it known that I, JACKSON L. PRIOR, a citizen of the United States, residing at Fayetteville, in the county of Cumberland and State of North Carolina, have invented certain new and useful Improvements in Non-Refillable Bottles, of which the following is a specification, such as will enable those skilled in the art to which it appertains to make and use the same.

The object of this invention is to provide a bottle, jug, jar, or similar vessel which having been once filled and sealed cannot be refilled or reused.

The invention is fully disclosed in the following specification, of which the accompanying drawing forms a part, in which the separate parts of my improvement are designated by suitable reference characters, said drawing being a central vertical section of a bottle made according to my invention.

In the practice of my invention, as shown in the drawing, I provide a bottle *a* of the usual or any preferred form and the bottom 25 of which is provided centrally in the form of construction shown with a tubular filling-orifice *a*², which is closed by a ground-glass stopper *b*, which in practice is secured in position by glass, cement, or any other suitable 30 material and cannot be removed.

The bottle *a* is provided with two necks *a*³ and *a*⁴. The neck *a*⁴ is made in the form of an inverted **U** or in the form of a half-circle, and the nozzle thereof is directed downwardly, 35 as shown at *a*⁵, and the neck *a*³ may be formed and secured to the bottle after the bottle has been made, or it may be formed at the same time as the rest of the bottle, and the neck *a*³ fully incloses the neck *a*⁴ and forms a chamber which extends above and around the neck *a*⁴. I also provide a closure device *c* for the 40 neck *a*⁴ or the nozzle *a*⁵ thereof, and this closure device is provided with a cord *c*², and the neck *a*³ is adapted to be closed by an ordinary stopper *d* in the usual way, or said neck *a*³ may be closed in any desired manner.

In practice the closure device *c* is inserted into the nozzle *a*⁵ of the neck *a*⁴ or secured thereto in any desired manner by a suitable 50 paste or cement, and the cord or other flexible device *c*² is left hanging in the neck *a*³ of the bottle. The bottle *a* may then be filled

through the filling-orifice *a*², after which the plug or stopper *b* is secured in place, as hereinbefore described. The neck *a*³ may then 55 be closed by the stopper *d* or, if desired, the closure of the neck *a*³ may be accomplished before the bottle *a* is filled. Whenever it is desired to empty the bottle *a* or discharge a portion of its contents, the stopper *d* is removed from the neck *a*³ and the cord or other flexible device *c*² is pulled, so as to remove or detach the stopper or closure device *c* from the neck *a*⁴, after which the contents of the bottle may be discharged by tilting it or inverting it in the usual manner. After the bottle 60 has been emptied of its contents it cannot be refilled by pouring liquids into the neck *a*³, for the reason that when the liquids rise to the discharge end of the neck *a*⁴ in the neck *a*³ the air in the bottle *a* will prevent said liquids from flowing into the bottle. 65

The neck *a*⁴ of the bottle is also preferably provided with a valve *e*, which opens outwardly but closes inwardly, and this valve 75 will prevent any successful effort to fill the bottle by holding it on its side and forcing liquids into the neck *a*³.

My invention is not limited to the exact form of the neck *a*⁴, as any loop-shaped neck 80 will do, nor is my invention limited to the particular construction of the stopper or closure device *c* used in connection with said neck, and various changes in and modifications of the construction herein described 85 may be made without departing from the spirit of my invention or sacrificing its advantages, and I reserve the right to make all such alterations therein as fairly come within the scope of the invention. 90

Having fully described my invention, what I claim as new, and desire to secure by Letters Patent, is—

1. A bottle of the class described, provided with two necks one of which incloses the other, 95 the inner neck being in the form of a loop and the nozzle thereof directed downwardly, means for closing the inner neck, and a device for closing the outer neck, the body of the bottle being also provided with a filling-orifice 100 and means for permanently closing the same, substantially as shown and described.

2. A bottle of the class described, provided with two necks one of which incloses the other,

the inner neck being loop-shaped in form and the nozzle thereof directed inwardly, said inner neck being also provided with a valve which opens outwardly, and the body of the 5 bottle being also provided with a filling-ori-
fice and means for permanently closing the same, substantially as shown and described.

In testimony that I claim the foregoing as

my invention I have signed my name, in pres-
ence of the subscribing witnesses, this 23d 10
day of May, 1903.

JACKSON L. PRIOR.
